UNITED STATES PATENT OFFICE.

HERMANN AUGUST THORVALD WAHNÖE, OF COPENHAGEN, DENMARK.

CRYPTOGRAPH.

Application filed March 28, 1923. Serial No. 628,237.

To all whom it may concern:

Be it known that I, HERMANN AUGUST THORVALD WAHNÖE, a subject of the King of Denmark, residing at Copenhagen, in the 5 Kingdom of Denmark, have invented new and useful Improvements in Cryptographs, of which the following is a specification.

The present invention relates to an automatic cryptograph which in consequence of 10 its nature may be used for a number of various purposes.

The distinguishing feature of the present cryptograph is one or more sets of double drums—in the following referred to as 15 duplex alternators—being each in similar manner as the commutator of an ordinary electromotor fitted with a number of segments, the said segments being electrically interconnected from drum to drum 20 and from one duplex alternator to the other one in any suitable manner, the said duplex alternators with their interconnections being inserted as electrical intermediate members between the keys in 25 a letter key-board and moving mechanisms for a system of type levers, the said keys when operated in ordinary manner actuating the type levers by electrical means and, at the same time, causing the interposed 30 duplex alternators to alter their mutual position, so as to effect a constantly varied mutual transposition of the letters of the alphabet, numerals and signs.

The invention is shown in outline on the 35 drawing, in which—

Fig. 1, is a diagrammatic view of my invention.

Fig. 2 is a plan view of the system of duplex alternators and the means for operating 40 the same, and

Fig. 3 is a side view of the driving mechanism for the same.

The number of segments on each duplex alternator is adjusted according to the number of alphabet letters with accompanying numerals, signs, spaces etc. Supposing for instance the number of letters, signs etc. to be fifty in all, then there must necessarily by fifty segments on each of the double alternators. Against each of these segments, which are marked L on the drawing, rests a small brush or carbon not shown on the drawing, however.

On the drawing, the duplex alternators V_1 , V_2 and V_3 are shown as drums v_1 and v_2 disposed inside of one another (v_{11} and v_{1y} , v_{21} and v_{2y} and v_{31} and v_{3y} , respectively), the said arrangement being selected mostly for the sake of clearness, although in practice there is really nothing to prevent such construction. Preferably, however, the two drums of the duplex alternators should be disposed one below the other one, and the space between them in which the connections pass from the segments on one drum to the segments on the other one should be 65 enclosed.

Each of the segments on the outer drum v_{1y} in the duplex alternator V_1 to the left in the Figure is connected, by way of a switch S, with one of the push buttons or keys T in a letter keyboard. From the inside drum v_{11} in the same duplex alternator V_1 , the connecting wires pass each from the brushes to a segment on the outer drum v_{2y} in the next duplex alternator V_2 , and from the inner drum v_{21} of this duplex alternator onto the segments on the inner drum v_{31} of the duplex alternator V_3 , the segments of the outer drum v_{3y} of the latter being each, by way of the switch S, connected to a magnet coil M, for instance one magnet coil for each letter, numeral sign, etc., the said magnet coils each actuating one type lever of a set of type levers as in ordinary writing machines or ordinary printing telegraph apparatuses. The cryptograph, however, may also be combined with a perforating machine driven for instance by compressed air and a printer, which is inserted in order to reproduce the message in shape of ordinary letters.

If now the position of the duplex alternators remained unaltered, then each of the letter keys or push buttons T, when depressed, would always actuate one definite type lever, and the letter concerned would thus always be reproduced in one and the same manner. In the present cryptograph, however, automatic transposition of alphabet letters, numerals and signs is provided for by the arrangement that the first duplex alternator V_1 , whenever a push button or key in the key board is depressed, or has been depressed, automatically—by electrical or mechanical means—makes $\frac{1}{n}$ of a rev-

olution, n being the number of segments on the periphery, i. e. one segment forward for each depression of a key.

Whenever in this manner the duplex alternator V_1 has made a full revolution, then the next duplex alternator in the series, here V_2 , advances also one segment, and for each full revolution of this duplex alternator also the third alternator V_3 , advances one segment forward, and so forth, whereby a very large number of variations will be attained.

On the drawing three duplex alternators are shown, but any number may be used, and the number of variations will increase with the number of alternators used. Instead of the alternators, as mentioned above, rotating forward one segment at a time, there is nothing to prevent them from rotating two or more segments forward at a time, and the rotation may be performed in irregular manner, for instance in leaps of now one, then two, then one, then three segments, all according to the adjustment of the cryptograph.

25 The manner of action of the cryptograph will appear from the following example.

If, for the position of the duplex alternators and the switch S shown on the drawing, for instance the key T is depressed for 30 the letter C , then current will pass from the battery 11 by way of the conductors 12 and 13, the contact 14, the conductor 15, the switch S , the conductor 16 to the segment 6 on the drum v_{1y} , thence by way of a not 35 shown fixed connection to the segment 6 on the drum v_{11} , and further on by way of the conductor 17 to the segment 5 on the drum v_{2y} , then by way of not shown conductor to the segment 5 on the drum v_{21} , thence by 40 way of the conductor 18 to the segment 4 on the drum v_{31} , thence by way of a not shown conductor to the segment 4 on the drum v_{3y} , and thence by way of the conductor 19, the switch S , the conductor 20, 45 the magnet coil M for the type lever supporting the type E and back to the battery 11. The letter C is thus in this case reproduced as the letter E . When the key is released and, thereby, the circuit is broken, 50 then the duplex alternator V_1 advances one segment forward. When the key is now again depressed for the letter C , the current passes as before from the battery 11 by way of conductors 12 and 13, contact 14, 55 conductor 15, switch S and conductor 16, but now to the segment 5 on the drum v_{11} , the said segment 5 occupying now the former position of the segment 6. From the segment 5 the current passes on by way 60 of a not shown conductor to the segment 5 on the drum v_{1y} , thence by way of the conductor 21 to the segment 6 on the drum v_{2y} , and from there, by way of a not shown conductor, to segment 6 on drum v_{21} , and 65 by way of conductor 22 to segment 3 on

drum v_{31} , by way of a not shown conductor to segment 3 on drum v_{3y} , and from here by way of conductor 23, switch S , conductor 24, magnet coil M for the type lever supporting the type D and back to the battery 70 11, in such a manner that the letter C is now reproduced as the letter D , while immediately before it was reproduced as the letter E .

Referring to Figs. 2 and 3, which show the operating mechanism for the alternators, a is a key and b the key lever which is pivotally mounted at c . On the opposite end of the lever b from the key a is a switch d , so that as the lever is operated, circuit is made 80 from the battery e through the conductors f and g , the electromagnet h and the conductor i . The armature j is thus attracted by the electro-magnet h , and rotates on the shaft k which carries the armature. At the upper end of the armature j is mounted a pawl m which engages a ratchet wheel n , carried by the shaft k and connected to the drum v_{1y} , so that upon each attraction of the armature, the ratchet wheel n and the 90 drum v_{1y} will be rotated one step. In this manner the drum v_{1y} is rotated with respect to the drum v_{11} , which is stationary upon the shaft.

Whenever the alternator v_{1y} is rotated a 95 complete revolution by the operation of a key, a number of consecutive times, a wheel s is rotated by means of gears q and r , and a tooth t carried on the wheel s engages a gear u and moves it forward one step. This 100 gear u is secured to the drum v_{2y} so that corresponding rotation of this drum one step is accomplished. It will thus be seen that upon the complete rotation of the first drum, a movement of one step forward is imparted 105 to the second drum. In the same manner, rotation is transmitted to the third drum upon completion of a complete revolution by the second drum. Rigidly secured to the shaft k is a handle w by means of which the 110 drums may be rotated backwards to initial position.

The deciphering is effected in exactly the same manner as the here described ciphering, only that in case of deciphering the 115 switch S should occupy the opposite position of the ciphering position, so that the current will now pass through the duplex alternators in the direction opposite the one indicated above.

In deciphering care must also be taken that all the duplex alternators when deciphering commences occupy exactly the same position as occupied by the same members, when the ciphering of the same message 125 was commenced. In order to facilitate such adjustment, each of the duplex alternators should be fitted with a mark indicating the initial position. When now, after the cryptograph has been properly adjusted in this 130

manner, the cipher message at hand is written on the letter keys of the cryptograph, then the type levers will be moved automatically in such a manner that the message will be reproduced in the original language.

Having thus described my invention, what I claim is:—

1. An automatic cryptograph apparatus comprising a plurality of alternators, each 10 consisting of an outer annular rotatable body, and an inner body, each body having alternately disposed electrical contacts arranged thereon and in circuit with each other, the said alternators being in series 15 with a key-board and type lever actuating means, the operation of the keys closing the circuit to rotate the outer bodies with respect to each other and also with respect to the inner annular body, so as to change their 20 mutual relation thereby effecting a constantly varied mutual transposition of symbols.

2. An automatic cryptograph apparatus

comprising a plurality of alternators consisting of annular rotatable bodies having 25 spaced contacts thereon, a key-board and type levers, and means for electrically connecting the alternators in series with the key-board and type levers, the operation of the keys effecting rotation of the alternators 30 and causing one of the alternators to rotate a complete revolution upon the successive operation of the keys, the second and third alternators being adapted to advance one step when the next preceding alternator has 35 completed its revolution, whereby the mutual relation of the alternators is changed and effects a constantly varied mutual transposition of symbols.

In testimony whereof I have signed my 40 name to this specification.

HERMANN AUGUST THÓRVALD WAHNÖE.
